DESIGN FOR A PNEUMATIC TIRE

John E. Cady, Donald A. Macdonald, and Ralph G. Null, Indianapolis, Ind., assignors to United States Rubber Company, New York, N. Y., a corporation of New Jersey

Application December 14, 1939, Serial No. 88,887

Term of patent 14 years

To all whom it may concern:

Be it known that we, John E. Cady, Donald A. Macdonald, and Ralph G. Null, citizens of the United States of America, residing in Indianapolis, county of Marion, State of Indiana, have invented a new, original, and ornamental Design for a Pneumatic Tire, of which the following is a specification, reference being had to the accompanying drawing, forming part thereof, wherein:

Figure 1 is a plan view of a portion of a tire embodying the ornamental design;

Figure 2 is a transverse view, in section, taken along line II—II of Figure 1; and,

Figure 3 is a side view of a portion of the tire.

We claim:

The ornamental design for a pneumatic tire, as shown.

JOHN E. CADY.
